THREAD WINDING MACHINE

Filed Jan. 22, 1948

UNITED STATES PATENT OFFICE

2,535,984

THREAD WINDING MACHINE

William E. Mahoney, Pawtucket, R. I., assignor
to Premier Thread Company, a corporation of
Rhode Island

Application January 22, 1948, Serial No. 3,712

6 Claims. (Cl. 242—31)

1

This invention relates to a thread winding machine and more particularly to a mechanism for the formation of a package with a tapered end.

In winding machines of the character here referred to, the traverse for guiding the thread upon the package presses upon the package by reason of the same being mounted upon a weighted lever. The arrangement is such that as the package fills up, the portion which presses upon the package is moved further from the axis by swinging about its pivot. However, this pressure of the traverse guide upon the package causes a tight or hard wind, making a rather hard package, and this is true even though the weight is counterbalanced to a large extent.

One of the objects of this invention is to provide an arrangement whereby a soft package, or one that is not wound as tightly as heretofore, may be provided.

Another object of this invention is to guide the yarn to the package without causing the guiding beams to contact the package, so that this pressure and contact will not cause the hard wind, where the same is undesirable.

Another object of this invention is to remove the pressure from the individual thread as it is delivered to the take-up package.

Another object of the invention is to utilize the broad surface of the roll which controls the axial movement of the package by contact with the surface of the package and the conical base for controlling the movement of the thread guide in its desired relation to the surface of the package.

With these and other objects in view, the invention consists of certain novel features of construction as will be more fully described and particularly pointed out in the appended claims.

In the accompanying drawings:

Figure 1 is a fragmental end elevation showing a portion of a winding machine with the improved mechanism in position thereon;

Figure 2 is a fragmental side elevation of the improved parts shown in Figure 1;

Figure 3 is a fragmental elevation similar to Figure 2, but illustrating some of the parts removed to better expose other parts;

Figure 4 is an elevation of the contact or follower roll which engages the surface of the package and also governs the axial movement of the package; and

Figure 5 is a diagrammatic view showing the thread guide spaced from the package.

In proceeding with this invention, I modify the winding machine, such as illustrated in my Patent 2,099,985 dated November 23, 1937, by con-

2

necting together through gears the swinging mechanism which carries the traverse guide for the thread, and the swinging mechanism which engages the surface of the package and the conical base, so that as one of these move, the other will move correspondingly with reference to the axis of the package, the arrangement being such that both will move toward the axis of the package or both will move away from the axis of the package in unison. By this arrangement, the means which urge one of these swinging parts toward the axis of the package will also urge the other one toward the axis of the package, and by this arrangement, I may mount the traverse guide at a distance spaced from the package a predetermined amount, and as the package fills up, this spacing between the surface of the package and the traverse guide will be maintained constant throughout the building of the package, and by this spacing, I may cause a very soft or light wind to occur that the package will not be hard or tight which is especially important where synthetic filamentary yarns are used.

The winding machine here partly illustrated is of the type well known on the market, and illustrated in patents owned by the Universal Winding Machine Company and the Foster Machine Company and others, wherein a package is formed upon a core having a conical base, with the arrangement such that there is a conical end formed on the package. In Figure 1, I have indicated the end of one such winding machine, the body of which is designated 10 having a stud 11 extending therefrom upon which is rockably mounted a frame 12, a counterweight designated 13 is located at one end of this frame and tends to swing the frame to a vertical position. The thread guide consisting of a porcelain disk 14 having a notch 15 for insertion of the thread is carried by this frame and guides the thread as it builds up its diameter on a package. The body 10 of the machine is provided with an arc shaped member 16 against which a friction rod 17 pivoted as at 18 to the frame 12 is adapted to bear during the winding operation. This frame provides one arm of the mechanism or means which form the subject of this invention.

The package mandrel is designated generally 20 upon which there is mounted a bobbin 21 having a barrel portion 22 and a tapered or conical base 23. The mandrel is driven by a pulley from some suitable source, not shown, and rotation is controlled by a clutch 24 which may be operated by a handle 25 shown as extending upwardly in Figures 1 and 2. The mandrel and

bobbin thereon are so arranged as more fully described in my prior Patent 2,099,985 as to tend to move to the right as shown in Figures 2 and 3 as the yarn is wound thereon. In order that the endwise movement of the bobbin may be controlled, a follower roll 27 is mounted on the end of an arm 28 which is pivotally mounted as at 29 by a stud threading into the frame 10 so as to swing about the axis of this stud to cause the roll 27 to move away from the axis of the mandrel 20 as the package builds up. This roll engages the surface of the package and its end also engages the conical base 23. The conical base is permitted to move axially or endwise only in accordance with the amount that the roll moves outwardly away from the axis of the package. All as more fully described in my above-mentioned patent.

The roll 27 rotates on the axis of a shaft 30 which is mounted in a frame-like structure 31 having a base 32 which is slidable in the guide ways 33 formed by portions 34 of the laterally extending portion 35 of the arm of frame 28. A bracket 36 is secured to the end of the lateral portion 35 and carries a screw 37 having a threaded end 38 which has threaded engagement with the frame 32, while a spring 39 tends to move the frame away from the upright portion 40 of the bracket, or the same may be drawn toward the upright portion by suitable manipulation of the screw 37. Thus, the position of this roll 27 with reference to the arm 28 may be nicely adjusted.

A portion of a gear 41 is mounted on the pivotal axis 29 of the arm 28, and is fixed to this arm so as to move therewith by reason of there being fixed to the gear an extension 42 which lies along the arm 28 and is secured in adjusted position about the axis 29 by reason of a slot 43 in this portion and a threaded pin 44 extending through the slot and into the arm 28, so as to hold this gear in adjusted position relative to the arm, and in order to assist in the adjustment of this gear, relative to the arm, a screw 46 extends through a boss in the portion 42 and bears against the arm 28 with a spring encircling this screw, so that by turning the screw in a right-hand direction, the gear will be rotated about the pivot with reference to the arm clockwise, which will be assisted by the spring; whereas, if the screw is turned in the opposite direction, the spring will force the arm so as to turn the gear counter-clockwise with reference to the arm 28.

The gear 41 meshes with a gear 48 which is fixed to the arm 12 by means of a U-shape bracket 49 with which it may be cast integrally and having end portions 50 and 51 secured by means of screws 52 and 53 to the arm 12. The U shaped bracket is such as to straddle the knob 55 which is a customary part of the machine.

From the above, it will be readily apparent that I may substitute an arm carrying the follower roller with a gear thereon for the one usually used, such as shown in my above-mentioned patent, and provide a bracket with a gear to be secured to the arm carrying the traverse guide, and that by this arrangement and the swinging of the gear 41 about its pivot 29 by reason of the screw 46 I may cause the follower roll 27 to engage the surface of the package in Figure 5, while by reason of the gear connection of this arm 28 to the arm 12, I may cause the porcelain thread traverse guide 14 to be spaced from the surface of the package, as shown in Figure 5. Thus, as the package builds up, the

arm 28 will swing about its pivot 29 to the left, as shown in Figure 1, and through the gears will correspondingly move in unison the spaced thread guide away from the axis of the package on the other side thereof, thus insuring all of the time that as the thread is being delivered to the package, the traverse guide will be spaced from the package and a loose or soft wind of thread in package form will result. I may control the compactness of wind of the package by merely adjusting the screw 46 so as to permit the traverse guide to be positioned closer to or further from the axis or surface of the package as it is wound, which is extremely important where synthetic yarns such as nylon and the like are used.

I claim:

1. In a machine for winding a package on a core, an arm pivoted on an axis parallel to the axis of the package to rock toward and from the axis of the package, a roll carried by said arm to rotate on an axis parallel to the package and of a substantial axial extent to engage the surface of the package, and be moved away from the axis of the package by the package as the same increases in diameter, a second arm pivoted on an axis parallel to the axis of the package to rock toward and from the axis of the package, a thread guide for delivering thread to the package carried by said second arm, gears carried by said arms in meshing relation and means to urge at least one of said arms toward said package whereby swinging movement of the first arm will cause a swinging movement of the second arm in response thereto and whereby said thread guide may be caused to follow the surface of the package without contacting the same.

2. A machine for winding a package as in claim 1 wherein said thread guide is adjustable relative to the arm on which it is mounted to cause an adjustment of the space to be maintained by the guide from the surface of the package throughout the increase of the diameter of the package.

3. In a machine for winding a package on a core having a frusto conical base which is urged axially, an arm pivoted on an axis parallel to the axis of the package to rock toward and from the axis of the package, a roll carried by said arm to rotate on an axis parallel to the package and of a substantial axial extent to engage the surface of the package and said frusto conical base and be moved away from the axis of the package by the package as the same increases in diameter to permit axial movement thereof, a second arm pivoted on an axis parallel to the axis of the package to rock toward and from the axis of the package, a thread guide for delivering thread to the package, carried by said second arm, gears carried by said arms in meshing relation and means to urge at least one of said arms toward said package whereby swinging movement of the first arm will cause a swinging movement of the second arm in response thereto and whereby said thread guide may be caused to follow the surface of the package without contacting the same.

4. A machine for winding a package as in claim 3 wherein said thread guide is adjustable relative to the arm on which it is mounted to cause an adjustment of the space to be maintained by the guide from the surface of the package throughout the increase of the diameter of the package.

5. In a package winding machine, a traverse guide for delivering thread to the package being formed, and means to space the guide at a predetermined distance from the surface of the pack-

age being formed and follow the surface at the predetermined distance as the package changes in diameter, said means comprising a pair of arms movable toward and away from the axis of the package simultaneously from opposite sides thereof.

6. In a package winding machine, a traverse guide for delivering thread to the package being formed, and means to space the guide at a predetermined distance from the surface of the package being formed and follow the surface at the predetermined distance as the package changes in diameter, said means comprising a pair of arms

5 connected by gears to be movable toward and away from the axis of the package simultaneously from opposite sides thereof.
